D6-582

EX

OF D 5,761

UNITED STATES PATENT OFFICE.

HENRY KAGY, OF PHILADELPHIA, PENNSYLVANIA, ASSIGNOR TO THOMAS POTTER, SON & COMPANY, OF SAME PLACE.

DESIGN FOR AN OIL-CLOTH PATTERN.

Specification forming part of Design No. 5,761, dated April 9, 1872.

To all whom it may concern:

Be it known that I, HENRY KAGY, of the city and county of Philadelphia, in the State of Pennsylvania, have invented and produced a new and original Design for Oil-Cloths for table-covers and other purposes; and I do hereby declare the following to be a specification thereof:

The nature of my design is fully shown in the accompanying photographic illustration, which forms a part of this specification and represents one-fourth of the said design as applied to a square table-cover. The remaining three-fourths are exactly similar to the fourth shown, and are so arranged with reference to it, in the complete design, as to form a central figure surrounded by a square border. Should the outline of the cover be any other figure than a square the general outline of the border may be made to correspond

therewith. The central figure may be arranged somewhat more symmetrically than shown in the illustration by making its straight lines either parallel to the corresponding sides of the border or inclined thereto at an angle of forty-five degrees.

What I claim as my invention, and desire to secure by Letters Patent of the United States, is—

1. The central figure, substantially as shown and described.
2. The border, substantially as shown and described.
3. The entire design, substantially as shown and described.

HENRY KAGY.
